UNITED STATES PATENT OFFICE.

DANIEL A. TOMPKINS, OF CHARLOTTE, NORTH CAROLINA.

BOLSTER-RAIL FOR SPINNING-FRAMES.

SPECIFICATION forming part of Letters Patent No. 727,715, dated May 12, 1903.

Application filed December 17, 1902. Serial No. 135,547. (No model.)

To all whom it may concern:

Be it known that I, DANIEL A. TOMPKINS, a citizen of the United States, residing at Charlotte, county of Mecklenburg, State of North Carolina, have invented certain new and useful Improvements in Bolster-Rails for Spinning-Frames, Twisting-Frames, and the Like; and I do hereby declare the following to be a full, clear, and exact description of the invention, such as will enable others skilled in the art to which it appertains to make and use the same.

My invention relates to certain new and useful improvements in bolster-rails for spinning-frames, twisting-frames, and the like, and is designed particularly to dispense with the customary individual lubricating feed-tube heretofore employed for supplying the lubricating-oil to the spindle bearings or bolsters and to substitute therefor a reservoir common to an entire series of spindles and of such capacity as to supply the necessary lubrication to the series without renewal during a long period of time. To this end I substitute for the ordinary bolster-rail, of angle-iron or the like, a hollow casting adapted to receive the lubricating-oil and provided, if desired, with a supplemental compartment or compartments whose purpose is to give any head that may be considered desirable by the operator. In practice it will be found convenient to cast the hollow bolster-rail in a number of sections whose hollow interiors may communicate with each other through the intermediary of connecting-nipples, or, if preferred, the sections may be put into communication with each other by means of by-pass pipes located on the rear side of the bolster-rail, so as to be out of the way.

In the accompanying drawings, Figure 1 represents a cross-sectional view of a bolster-rail constructed in accordance with my invention, one of the spindles and its adjuncts being shown in elevation. Fig. 2 represents a like view with the spindle-bolster in section. Fig. 3 represents a view similar to Fig. 1, but showing a different and adjustable manner of connecting the spindle-bolster to the rail. Fig. 4 represents, on a smaller scale, partly broken away, a longitudinal section of the bolster-rail and supplemental head-chamber

and illustrates a number of spindle-bolsters in place.

Similar letters of reference indicate similar parts throughout the several views.

The hollow bolster-rail sections may conveniently be cast and will be of suitable internal dimensions to contain a supply of lubricating-oil sufficiently ample to maintain the lubrication of the bearings throughout a long-continued period of time. In the drawings, A indicates one of these sections, and a

55

the lubricating-oil contained therein.

The hollow bolster-rail is provided with a series of holes or apertures spaced at suitable distances apart for the reception of the bearings or bolsters of the individual spindles. As shown in Figs. 1, 2, and 4, the outer shell or tube b of each bearing is screw-threaded at c, and the receiving-apertures are correspondingly screw-threaded, so that the bearings will maintain a fixed relationship to the bolster-rail. In the modification shown in Fig. 3, however, the screw-threaded connection is dispensed with, and the relation of the bearings to the apertures within which they have a limited play is regulable by means of the adjusting-nut d and the screw-bolt e, the aperture through which the bolt-shank passes giving sufficient capacity of adjustment to effect the limited centering movement desired. The tube b of the journal-bearing is perforated, so as to permit the free access of oil into its interior. Usually a few perforations will suffice; but they may be increased in number, as indicated, should particular circumstances so require.

It will of course be understood that the invention is applicable to spindles and spindle-bolsters of the ordinary type, for which reason I have not thought it necessary to do more than illustrate generally a suitable construction, which will be well understood by those skilled in the art.

In the practice of my invention the several sections A of which the hollow bolster-rail is made up are joined together end to end, as hereinbefore set forth, and the spindle bearings or bolsters are inserted in place with their lower ends immersed in the body of lubricating-oil. For most if not for all purposes and for most lubricating fluids it will

suffice to maintain the body of oil at such a height as to keep the spindles well submerged at the step-bearings, the oil entering freely through the apertures *g*. Usually, however, 5 and in order that the supply may last for a longer period the hollow interior of the bolster-rail is filled with lubricating-oil at the outset, the supply being renewed from time to time as required. The oil supplied to the 10 step-bearings will in most instances readily rise to lubricate the remaining portions of the bearing; but if it is found desirable to supplement the natural rise due to the rotation of the spindle by a more positive supply this may be effected by employing a supplemental chamber or chambers designed to give a sufficient head to positively maintain the oil at a level corresponding to the height of the highest bearing-surface of the 15 spindle, as indicated by the dotted line in Fig. 4. To this end a supplemental chamber *B* may be located conveniently at each end of the hollow bolster-rail, so as to communicate therewith through an aperture *h*. The 20 chamber *B* may be either a separate casting, as shown, or it may be cast as part of the bolster-rail. The oil may be conveniently supplied to the hollow rail and to the supplemental chambers themselves through a filling-aperture in each of the supplemental chambers. 25 By regulating the level of the oil in the supplemental chambers the level of the oil in the bearing-tubes *b* can be positively assured and determined without relying upon the tendency 30 of the rapidly - revolving spindle to bring the oil to the proper level should that tendency in any particular case prove insufficient.

Another element of advantage incident to 35 my invention is that the body of oil in the bolster-rail has a tendency to keep the bolster-rail at a uniform temperature. Any tendency to heat in any one spindle would therefore be corrected by the circulation of the oil. Consequently the danger of springing 40 or warping of the rail by heat at any one point is minimized.

My invention also affords improved facilities for readily and effectually cleaning the

bolsters and spindles without removing them 50 from the bolster-rail. To this end the body of lubricating-oil may be drawn off at any time and its place supplied with kerosene or the like. The spindles are then again put in motion, and after the cleaning operation is 55 completed the kerosene is withdrawn and steam or its equivalent is admitted for the purpose of removing any remaining traces of the kerosene. A fresh supply of lubricating-oil is then admitted to the chamber. 60

Having thus described my invention, what I claim is—

1. A bolster-rail having an oil chamber or tank for the reception of and in combination with a corresponding series of spindle bearings or bolsters, said spindle bearings or bolsters dipping in common into said chamber so that the same body of oil will occupy the space about and between the submerged portions of the series of bolsters; substantially 70 as described.

2. A bolster-rail having an oil chamber or tank for the reception of and in combination with a corresponding series of spindle bearings or bolsters, said spindle bearings or bolsters dipping in common into said chamber so that the same body of oil will occupy the space about and between the submerged portions of the series of bolsters, and slot-and-bolt connections between the rail and bolsters for centering the latter; substantially 75 as described.

3. A bolster-rail having an oil chamber or tank for the reception of and in combination with a corresponding series of spindle bearings or bolsters, said tank consisting of a longitudinal trough-like chamber into which said spindle bearings or bolsters dip in common so as to be immersed in and surrounded by the same body of oil; substantially as described. 85

In testimony whereof I affix my signature in presence of two witnesses.

DANIEL A. TOMPKINS.
